UNITED STATES PATENT OFFICE.

WINIFRED E. JONES, OF MILWAUKEE, WISCONSIN.

SUPPORT FOR SURGICAL NEEDLES.

1,198,450.

Specification of Letters Patent. Patented Sept. 19, 1916.

Application filed January 14, 1916. Serial No. 72,016.

To all whom it may concern:

Be it known that I, WINIFRED E. JONES, a citizen of the United States, and resident of Milwaukee, in the county of Milwaukee and 5 State of Wisconsin, have invented new and useful Improvements in Supports for Surgical Needles, of which the following is a description, reference being had to the accompanying drawings, which are a part of 10 this specification.

The invention relates to supports for surgical needles for the removal of superfluous hair and blemishes of other character on the face or body of the patients.

15 In the use of these needles it is customary to use a number on the patient at a time as the strain on the patient is an extremely nervous one and consequently the work should be done in the shortest possible time. 20 The essential object of this invention is to provide a support or stand for carrying the needles and facilitate the operation of a number of them at the same time.

Heretofore it has been customary to provide a support extending over the head of the patient and from which the needles depend downwardly and when not in use dangle in front of the patient's face much to her annoyance and danger. It is another object 30 of this invention to provide an overhead support which may be extended over the head of the patient when in use and which is provided with a head piece provided with a number of needle-receiving pockets where- 35 by the needles may be supported above the head of the patient when not in use and this overhead support is also capable of being moved backwardly away from the patient.

When working on the face of a patient it 40 frequently happens that needles are in use on both sides of the face and to facilitate this I form the head piece in a semi-circular or semi-oval shape to substantially conform to the head of the person so that the needles 45 may be carried by it and be readily brought down to operative position.

The invention is further designed to provide a support in which the conductor cords for the needles may be readily moved out of 50 the way.

The invention further consists in the several features hereinafter set forth and more particularly defined by claims at the conclusion hereof.

In the drawings: Figure 1 is a view of 55 the device embodying the invention; Fig. 2 is a plan view thereof; Fig. 3 is a section taken on line 3—3 of Fig. 2; Fig. 4 is a section taken on line 4—4 of Fig. 2; Fig. 5 is a detail front view; Fig. 6 is a section taken 60 on line 6—6 of Fig. 2.

The device comprises an adjustable standard and needle supporting and holding means or carrier mounted thereon.

The standard comprises a base 10 to which 65 is secured a tube 11 in which a rod 12 is slidably mounted, and a set screw 13 passing through said tube 11 for securing the rod 12 in various positions of adjustment. The standard is adapted to be placed on the floor 70 and the needle-support carried thereby may be raised or lowered as desired by adjusting the position of the rod 12 in the tube 11.

The needle support and holding means comprises a terminal support, a head piece, 75 means for varying the position of the head piece with respect to the standard and terminal support and guide means carried by said terminal support and head piece.

The terminal support consists of a semi- 80 circular member or strip 14 of conducting material secured at its ends 15 to a trans- 85 verse member 16 which in turn is secured to the upper end of the rod 12. The member 14 is provided with a plurality of apertures 17 for receiving the needle plugs 18 and the 90 plug 19 which is connected to the main conductor 20 which is provided with a plug 21 for connecting said conductor to a source of electric current. Each needle plug 18 is con- 95 nected to its respective conductor cord 22 which carries a connector-plug 23 at its outer end. This plug 23 is detachably secured to the needle holder 24 which has a rear portion 25, an insulated portion 26 and carries 95 a needle 27 electrically connected to the plug 23.

The head piece consists of a semi-circular channel member 28 secured at its ends 29' to a transverse member 29, the flange portions 100

30 and 31 of said channel being provided with a series of registering notches 32 and 33 respectively. The width of the channel is preferably the width of the insulated portion 26 of the needle holder and the rear portion 25 of each holder is adapted to be seated in one of the notches 32 and the needle in one of the notches 33, a small centrally disposed notch 35 being provided in 10 the bottom of the slot 33 for receiving the needle. The shoulder 36 formed by the portion 26 with the portion 25 of the holder limits the rearward movement of the holder. It will be further noted that the needle being disposed in the notches in the flanges of the channel sections above the bottom 37 thereof, may be readily removed from the pocket formed by these notches by inserting the thumb and forefinger within the channel 20 on either side of the needle holder and lifting it upwardly out of the notches.

The means for varying the position of the head piece with respect to the standard and the terminal support comprises lazy tongs 38 25 pivotally secured to each other and pivotally secured at their outer ends 39 to an ear 40 on the member 29 and at their inner ends to an ear 41 on the member 16, the inward and outward movement of said tongs causing the inward and outward movement of 30 the head piece. This permits the head piece, carrying the needles, to be folded up against the standard when not in use. The tongs may be provided with adjustable nuts 38' for 35 securing said tongs in different positions.

The transverse member 16 is provided with a plurality of spaced apart notches 42 and the transverse member 29 with a plurality of corresponding notches 43 for receiving and guiding the needle-conductor cords 22 therein. The conductor cords 22 are slidably mounted in said notches 42 and 43 and the notches 32 and 33 in the channel member 28 so that the operator by grasping 45 any one or all of the cords in the space between the member 14 and the member 16 may pull upon it or them and thus draw the needle or needles carried thereby up out of the way and above the patient and into the 50 pockets formed in the head piece.

The operation of the device is as follows:—The rod 12 is adjusted in the standard to bring the carrier or needle support to the desired height and the head piece and 55 tongs are then moved outwardly the desired distance so as to bring the needles into position above the patient at the required point of treatment. The current from the source passes through the conductor 20 thence to 60 the terminal support 14 from whence it passes through the plugs 18 into the conductor cords 22 to the needles 27. The needle or needles are then removed from

their pockets and inserted beneath the skin or otherwise applied, according to the kind 65 of treatment required. Thus all the needles may be kept at work for any length of time and by the use of a plurality of needles the time during which the patient is under treatment is reduced thus lessening the strain on 70 the patient. Furthermore, when any of the needles are not in use they may be quickly drawn up out of the way and if desired into the pockets on the head piece where they will not annoy the patient or cause any injury. 75 Also the head piece may be moved back away from the patient when not in use and danger, due to dangling needles, prevented.

What I claim is:

1. A support for surgical needles comprising a supporting member, a terminal support carried by said member, a head piece, lazy tongs connecting said support to said head piece to permit it to be moved toward or away from said support, said terminal 80 support and head piece adapted to carry a main conductor and a plurality of needle-conductors, said conductors being movably guided in the head piece.

2. A support for surgical needles comprising a supporting member, a terminal support carried thereby, a head piece provided with a plurality of pairs of spaced apart registering notches forming needle-receiving pockets and connected to said support and movable with respect thereto, said support and head piece adapted to carry a plurality of needle-conductors, said conductors adapted to depend from said head piece when the needles are in use and to be pulled 90 back so as to seat the needles in said pockets when not in use.

3. A support for surgical needles comprising an adjustable supporting member, a terminal support carried thereby for receiving a main conductor of electric current and a plurality of electric needle conductors, a channel member forming a head piece provided with a plurality of pairs of registering notches forming needle-receiving pockets, notched guide members carried by said terminal support and head piece for receiving and guiding said needle conductors, and means pivotally connected to said head piece and terminal support to support said 105 head piece and permit of its movement with respect to said terminal support and supporting member, said needle conductors passing through the notches in said channel member and depending therefrom when in 110 use.

4. A support for surgical needles comprising an adjustable supporting member, a terminal support carried thereby for receiving a main conductor of electric current and 125 a plurality of electric needle conductors, a

head piece having a plurality of needle-receiving pockets formed therein, guide members carried by said terminal support and head piece for receiving and guiding said needle conductors, and extensible means connected to said head piece and terminal support to support said head piece and per-

mit movement of the headpiece with respect to said terminal support and supporting member, said needle conductors passing 10 through the pockets in the head piece when in use.

In testimony whereof I affix my signature.
WINIFRED E. JONES.
